[57] **ABSTRACT**

A mixing valve with a single operating handle enabling independent control of the discharge volume, the mixing ratio and the discharge direction of two miscible liquids. The mixing valve comprises a first valve member mounted in a valve housing for rotary movement relative to an adjacent fixed valve disc provided with two eccentric feeding passages for the miscible liquids, said first valve member having a transverse bore communicating with an internal inlet passage which in turn communicates dependent on the rotary position with one or both of the feed passages, a second valve member movable within said transverse bore between positions connecting said inlet passage to any one or none of two discharge lines, and an operating handle adapted to independently adjust the positions of both valve members.

MIXING VALVE

BACKGROUND OF THE INVENTION

The present invention relates to a mixing valve, and more particular to a mixing valve enabling independent control of the discharge volume, the mixing ratio and the discharge direction of two miscible liquids.

Such a mixing valves are generally known for mixing cold water and hot water, especially in bath rooms, can be used, however, also for other technical purposes.

There are already known many types of mixing valves for bath rooms which generally comprise a housing with two feeding lines for hot and cold water, two discharge outlets, usually leading to the bath-tub and the shower, respectively, first valve means for reciprocally controlling the cross section of the outlets for hot and cold water, second valve means for controlling the discharge volume, third valve means for controlling the discharge direction to either the bath-tub or the shower, and the necessary operating handles for actuating said first, second and third valve means. These known mixing valves suffer from the disadvantage that several operating handles have to be actuated in order to have the water flow with the desired rate and temperature through the chosen outlet.

Besides that there are known mixing valves having only one outlet, in which the valve means controlling the discharge rate and the mixing ratio are combined in such a way that they can be adjusted by a single operating handle. Such mixing valves are disclosed in German Patents 900 036, 1 021 668, 1 128 236, 1 144 982 and 1 149 211. None of these known mixing valves permits however, to direct the discharged liquid at will either to the bath-tub or to the shower. To this purpose it would be necessary to install an additional flow reversion cock of the known type so that again at least two handles have to be operated. Besides that the known mixing valves usually do not permit to maintain the mixing ratio when closing and reopening the valve. With other mixing valves it is possible to maintain the mixing ratio during closing and reopening, but the mixing ratio can only be adjusted in the closed position, so that it is not possible to adjust the mixing ratio while feeling the temperature of the discharged water.

SUMMARY OF THE INVENTION

It is, accordingly, an object of the present invention to overcome these disadvantages.

More particularly it is an object of the present invention to provide an improved mixing valve enabling independent control of the discharge volume, the mixing ratio and the discharge direction of two miscible liquids by a single operating handle.

It is a further object of the invention to provide a mixing valve which permits to maintain a certain mixing ratio when changing the discharge rate and/or the discharge direction.

A still further object of the invention is to provide a mixing valve which enables to adjust the mixing ratio and/or the discharge rate when feeling the temperature of the discharge water.

In accordance with the above objects and others which will become apparent hereafter, one feature of my invention results in the provision of a mixing valve comprising a valve housing having a valve receiving bore, a valve disc non-rotatably mounted in said valve receiving bore, a first valve member received in said valve receiving bore for movement about a rotary axis and having a valve face symmetrical to the rotary axis and fitted in sliding contact against the internal face of said valve disc, first and second disc passages disposed in said valve disc eccentrically and at a predetermined angular distance relative to the rotary axis of said first valve member, a transverse bore disposed in said first valve member, an inlet passage extending from the inner surface of said transverse bore to an opening eccentrically disposed on said valve face, said first valve member being movable relative to said valve disc between a first position in which said inlet passage communicates with said first disc passage, a second position in

which said inlet passage communicates with said second disc passage, and a plurality of intermediate positions, in each of which said inlet passage communicates with both disc passages in a certain predetermined ratio of cross-sections, first and second discharge passages extending from first and second points, respectively of the inner surface of said transverse bore to first and second outward openings, respectively, first and second discharge lines communicating with the outward openings of said first and second discharge passages, respectively, a second valve member received in said transverse bore and having a valve passage communicating with said inlet passage, said second valve member being movable between a first discharge position in which said valve passage communicates with said first discharge passage, a second discharge position in which said valve passage communicates with said second discharge passage, and an intermediate position in which said valve passage communicates with neither one of the discharge passages, first and second feed lines for said miscible liquids communicating with said first and second disc passages, respectively, and an operating handle mounted on said second valve member for the independent movement of said first and second valve members between the first, second and intermediate positions thereof.

According to a preferred embodiment there is provided a mixing valve wherein the transverse bore comprises a cylindrical central section, first and second cylindrical outer sections coaxial to said central section and having an increased diameter, and first and second transition sections disposed between said central section and said first and second outer sections, respectively, the inlet passage opens into said central section, said first and second discharge passages open into said first and second transition sections, respectively, said second valve member is received within said transverse bore for rotational and axial movement, said second valve member having mounted thereon first and second outward sealing rings sealingly engaging the inner surface of said first and second outer sections, respectively, of said transverse bore, and first and second inner sealing rings adapted to sealingly engage in the intermediate position of said second valve member the inner surface of the central section of said transverse bore, said second valve member further having an annular passage defined between said first and second inner sealing rings and communicating with said inlet passage, said second valve member being axially movable between first and second discharge positions, in which the respective one of the first and second inner sealing rings is moved out of contact with the central section of said transverse bore, thus providing a passage between said inlet passage and the respective one of the first and second discharge passages.

According to another embodiment there is provided a mixing valve wherein said transverse bore has a cylindrical inner surface, said second valve member is received in said transverse bore for only rotational movement, and is provided with a valve passage which in all rotational positions of said second valve member communicates with said inlet passage, and in certain different rotational positions of said second valve member communicates with one of said discharge passages.

At least one of said first and second discharge passages may extend to a circumferential annular groove on said first valve member, and the respective one of said first and second discharge lines may extend through the wall of said valve housing in a manner communicating with the respective annular groove. On the other hand one of said first and second discharge passages may communicate with a respective discharge line extending through said valve disc coaxially to the rotary axis of said first valve member. According to a further different embodiment one of said first and second discharge passages may communicate with a respective discharge line directly connected to said first valve member.

It is preferred to provide guide means mounted on said first valve member and restricting the movement of the operating handle relative thereto. Said first and second disc passages can be disposed close to each other in the same radial distance

from the rotary axis of the first valve member. It is also possible, however, to arrange said first and second disc passages in different radial distances from the rotary axis. In both cases it is preferred to adapt the shape and dimension of the opening of the inlet passage in such a manner that in the intermediate positions of said first valve member relative to said valve disc there are obtained cross-sections of communication with both disc passages which together permit an unreduced discharge rate.

A further embodiment of the mixing valve of the invention specifically adapted to the case that the hot water is produced in a flow heater, is characterized in that said valve disc is provided with a first disc passage disposed at a radial distance from the rotary axis of said first valve member and communicating with a first feed line for untreated liquid, a second disc passage disposed coaxially with said rotary axis and communicating via a connecting line to the outlet of a liquid treating device, and a third disc passage disposed in the same radial distance from said rotary axis as the first disc passage, said third disc passage communicating via a connecting line to the inlet of said liquid treating device, and said first valve member is further provided with a reversing channel separated from the opening of said inlet passage by a dividing edge which in accordance with the relative position of said dividing edge to said first disc passage provides for a corresponding partial flow through said reversing channel, said third disc passage, said liquid treating device and said second disc passage into said inlet passage.

This type of mixing valve can be used in other cases where it is desired to mix treated and non-treated portions of the same liquid.

The transverse bore provided in said first valve member can be closed after insertion of said second valve member by means of suitable cover plates. In this case each of said first and second transition sections may form an annular valve seat and said second valve piston biased by first and second spring means, respectively, against the respective annular valve seat. In this embodiment the operating handle is pivotally mounted and adapted to remove when pivoted to the one direction the first valve piston from the first valve seat, and when pivoted to the opposite direction to remove the second valve piston from the second valve seat.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanied drawings.

BRIEF DESCRIPTION OF THE DRAWINGS

FIG. 1 is a perspective view showing one embodiment of the novel mixing valve;

FIG. 2 is a vertical section through the mixing valve according to FIG. 1;

FIG. 3 is a horizontal section through the mixing valve seen in the direction of arrows from the line A—A of FIG. 2;

FIG. 4 is a cross-section through the mixing valve as seen in the direction of arrows from the line B—B of FIG. 2;

FIG. 5 is a vertical section through a modified mixing valve;

FIG. 6 is a horizontal section as seen in the direction of arrows from the line F—F of FIG. 5;

FIG. 7 is a cross-section through the mixing valve as seen in the direction of arrows from the line D—D of FIG. 5;

FIG. 8 is a cross-section corresponding to FIG. 7 through a further modified mixing valve;

FIG. 9 is a schematic section long the line G—G of FIG. 8;

FIG. 10 is a vertical section through a still further modified mixing valve;

FIG. 11 is a horizontal section through the mixing valve according to FIG. 10 along the line H—H;

FIG. 12 is a cross-section through the mixing valve of FIG. 10 along the line J—J; and

FIG. 13 is a schematic section through the mixing valve of FIG. 12 along the line L—L.

DESCRIPTION OF THE PREFERRED EMBODIMENTS

The mixing valve shown in FIGS. 1 to 4 comprises a valve housing 1 having a conical valve receiving bore 2 which communicates with a first discharge line 3 and a second discharge line 4. A first valve member 5 is received in the valve receiving bore 2 for rotary movement. The valve member 5 has a conical circumferential surface fitted into the inner wall of the bore 2, and a plane valve face 7 disposed vertically relative to the rotary axis and fitted in sliding contact against the plane internal face of a valve disc 15 which is non-rotatably mounted in the valve receiving bore 2 of the valve housing 1. The valve disc 15 is pressed against the first valve member 5 by means of a spring ring 30 kept in place by a circlip 34 snapped into an annular groove in the valve housing 1.

The valve disc 15 is provided with a first disc passage 16 connected to a first feed line 20 for cold water, and a second disc passage 17 connected to a second feed line 21 for hot water. The disc passages 16 and 17 are disposed eccentrically and at an angular distance relative to the rotary axis of the first valve member 5. The inner wall of the valve receiving bore 2 is provided with two radially inwardly projecting studs 33 which engage with corresponding marginal recesses of valve disc 15.

The first valve member 5 is shaped as shown in FIGS. 2 and 3 and provided with a transverse bore 8 which receives a second valve member 12 for rotary and axially sliding movement. The transverse bore 8 comprises a cylindrical central section 8a, first and second cylindrical outer sections 8b coaxial to said central section 8a and having an increased diameter, and first and second transition sections 8c disposed between said central section 8a and said first and second outer sections 8b, respectively. From the inner surface of the central section 8a of said transverse bore 8 there extends an inlet passage 9 to an opening eccentrically disposed on the valve face 7. In order to facilitate production this inlet passage 9 is disposed coaxially with the rotary axis and provided with an eccentric opening on the valve face 7. This eccentric opening extends radially outward to communicate in certain rotary positions of the valve member 5 relative to the valve disc 15 with one or both of the disc passages 16 and 17, respectively. In the position shown in FIGS. 2 to 4 the inlet passage 9 communicates via equal cross-sectional areas with the first disc passage 16 and the second disc passage 17 so that a mixture of equal parts of cold and hot water will be discharged. By a corresponding rotary movement of the first valve member 5 relative to the valve disc 15 any desired mixing ratio can be obtained. The shape and the dimensions of the eccentric opening of the inlet passage 9 on the valve face 7 should be chosen to obtain the same total cross-sectional area in all intermediate positions. In certain other cases it can be desirable to modify the eccentric opening of the inlet passage 9 to provide different cross-sectional areas in different intermediate positions.

The second valve member 12 is provided with first and second inner sealing rings 13 which in the position shown sealingly engage the inner surface of the central section 8a of the transverse bore 8. The second valve member 12 is further provided with first and second outer sealing rings 14 sealingly engaging the inner surface of the first and second outer sections 8b, respectively, of the transverse bore 8. Thus, there is formed an annular valve passage between said first and second inner sealing rings 13 and communicating with said inlet passage 9, and annular spaces between each inner sealing ring 13 and the corresponding outer sealing ring 14. In the first valve member 5 there are further provided first and second discharge lines 10 and 11, respectively, which communicate at their inner ends 10a and 11a with extend from the first and second transition sections 8c, respectively, of the transverse bore 8 and at the other ends thereof with corresponding annu-

lar grooves 23 and 24, respectively, disposed on the circumferential surface of the first valve member 5. To both sides and between said annular grooves 23 and 24 there are disposed sealing rings 22. The first annular groove 23 communicates with the first discharge line 3, whereas the second annular groove 24 communicates with the second discharge line 4.

An operating handle 27 is mounted by means of its U-shaped inner portion 26 on the second valve member 12 as clearly shown in FIG. 3. Secured to the first valve member is an obliquely slotted guide disk 35 restricting the movement of the operating handle 27 relative thereto so that pivoting the operating handle 27 causes rotational and axial movement of the second valve member 12 within the transverse bore 8. The guide disk 35 is provided with a pointer 36 movable between stop elements 37 on the valve housing 1 for restricting the rotational movement of the first valve member 5 relative thereto.

The modified embodiment of the mixing valve shown in FIGS. 5 to 7 is provided with a transverse bore 8 having a cylindrical inner surface. The second valve member 12 is of corresponding cylindrical shape and received in the transverse bore 8 for rotary movement without axial displacement. The inlet passage 9 is a straight bore disposed in parallel to the rotary axis. The opening of the inlet passage 9 on the valve face 7 and the disc passages 16 and 17 have substantially the same distance from the rotary axis. The first discharge passage 10 extends from the annular groove 23 to a point on the inner surface of the transverse bore 8 which is substantially in line with the rotary axis. The second discharge line 11 extends from the transverse bore 8 upwardly to an opening in the upper surface of the first valve member 5 which is outside the valve housing 1. A second discharge line can be directly mounted to the opening of the second discharge passage 11 on the first valve member 5.

The cylindrical second valve member 12 is provided with a valve passage which communicates with the inlet passage 9 in all possible rotational positions of the second valve member 12 relative to the first valve member 5. The valve passage on the other hand communicates in a first rotational position with the first discharge passage 10, and in a second rotational position with the second discharge line 11. In the embodiment shown in FIGS. 5 and 6, the valve passage comprises a straight radial through bore 12a connected by an axial passage 12b to a recessed slit 12c extending over abt. 90° of the circumferential surface, as indicated by the dotted line in FIG. 5. In the position shown in FIGS. 5 and 6 the recessed slit communicates with the inlet passage 9, and the straight thorough bore simultaneously communicates with the first discharge passage 10. If the second valve member 12 is turned counter-clockwise by lifting the bail 26 of the operating handle 27 by 90°, the recessed slit is still communicating with the inlet passage 9, whereas the straight thorough bore now communicates with the second discharge line 11. If the second valve member 12 is turned from the position shown in FIG. 5 counter-clockwise by only 45°, the straight thorough bore communicates with neither one of the discharge lines. The shape and the dimensions of the openings of the straight thorough bore should be chosen in order to obtain adequate discharge rate control.

In the position shown in FIGS. 5 and 6 the inlet passage 9 communicates via the disc passages 16 and 17, respectively, to the corresponding feed lines 20 and 21, respectively, via equal cross-sectional areas, as shown in FIG. 7. In this position the discharge water is again composed of equal parts of cold and hot water.

In FIG. 8 there is shown a modified version in which the disc passages 16 and 17 are disposed in different radial distances from the rotary axis of the valve member 5. In this embodiment the second disc passage connected to the second feed line 21 forms a widened recess on the internal face of the valve disc 15. The shape of this widened opening 21a is shown in FIGS. 8 and 9. In the position shown the discharged water will consist of a major part of cold water flowing from the cold

water feed line 20 into the opening 9a of the inlet passage 9, and a minor part of hot water flowing from the hot water feed line 21. If the first valve member 5 now is turned counter-clockwise there is first reached a position, in which the inlet passage 9 communicates with the cold water feed line 20 and the hot water feed line 21 via equal cross-sectional areas so that discharged water consists of equal parts of cold and hot water. If the first valve member 5 is turned further counter-clockwise, the discharged water contains more and more hot water and less and less cold water, until the inlet passage 9 comes out of communication with the cold water feed line 20. Now only hot water is discharged. If the first valve member 5 is turned still further counter-clockwise, due to the obliquely narrowed shape of the opening 21a, the discharge volume is more and more reduced. This is advantageous, in case the hot water is prepared by a flow heater, because for such flow heaters it is generally undesirable to prepare tepid water by mixing a large portion of cold water with a small portion of very hot water. According to the embodiment shown in FIGS. 8 and 9 the temperature of the hot water increases with the extent of counter-clockwise movement of the first valve member 5, and the throttling effect caused by the obliquely narrowing opening 21a serves to switch off the normal flow heater.

The modified mixing valve shown in FIGS. 10 to 13 generally corresponds to the embodiment shown in FIGS. 1 to 4, except for the inlet passage and the disc passages, which have been modified in order to adapt the mixing valve for the use in combination with a low pressure boiler. As shown in FIGS. 10 to 12, the first disc passage 16 is disposed at a radial distance from the rotary axis of the first valve member 5 and communicating with the cold water feed line, whereas the second disc passage 28 is disposed coaxially with said rotary axis and communicating via a connecting line to the outlet of the low pressure boiler. A third disc passage 17 disposed in the same radial distance from said rotary axis as the first disc passage, communicates via a connecting line to the inlet of said boiler. Besides that, the first valve member 5 comprises an additional reversing channel 32 recessed into the valve face 7 and separated from the inlet channel 9 by a dividing edge 31. In accordance with the relative position of said dividing edge 31 relative to the first disc passage 16 there is obtained a corresponding partial flow from the first disc opening 16 through the reversing channel 32, the third disc opening 17, the connecting line 18, a boiler (not shown), the connecting line 19, the second disc passage 28 into the inlet passage 9. This embodiment is especially suited for low pressure boilers.

The mixing valve of the invention is actuated by turning and/or pivoting the operating handle 27. A rotary movement of the operating handle 27 causes a rotary movement of the first valve member 5 relative to the valve disc 15 and a corresponding alteration of the mixing ratio. A pivotal movement of the operating handle 27 causes a rotary movement of the second valve member 12 relative to the first valve member 5 and thus adjusts the discharge rate. At the same time, the direction of the pivotal movement of the operating handle 27 decides, whether the water is discharged through discharge line 3 into the bath-tub (not shown), or through discharge line 4 to a shower (not shown).

It will be understood that each of the elements described above, or two or more together, may also find a useful application in other types of construction differing from the types described above.

While the invention has been illustrated and described as a mixing valve especially useful for mixing cold and hot water, it is likewise useful for many other similar technical purposes in which it is desired to enable an independent control of the discharge volume, the mixing ratio and the discharge direction of two miscible liquids by a single operating handle. Besides that, it is not intended to be limited to the details shown, since various modifications and structural changes may be made without departing in any way from the spirit of the present invention.

What is claimed as new and desired to be protected by letters patent is set forth in the appended claims.

I claim:

1. A mixing valve enabling independent control of the discharge volume, the mixing ratio and the discharge direction of two miscible liquids, especially cold water and hot water, by a single operating handle, said mixing valve comprising a valve housing having a valve receiving bore; a valve disc non-rotatably mounted in said valve receiving bore; a first valve member received in said valve receiving bore for movement about a rotary axis and having a valve face symmetrical to the rotary axis and fitted in sliding contact against the internal face of said valve disc; first and second disc passages disposed in said valve disc eccentrically and at a predetermined angular distance relative to the rotary axis of said first valve member; a transverse bore disposed in said first valve member; an inlet passage extending from the inner surface to said transverse bore to an opening eccentrically disposed on said valve face, said first valve member being movable relative to said valve disc between a first position in which said inlet passage communicates with said first disc passage, a second position in which said inlet passage communicates with said second disc passage, and a plurality of intermediate positions, in each of which said inlet passage communicates with both disc passages in a certain predetermined ratio of cross-sections; first and second discharge passages extending from first and second points, respectively of the inner surface of said transverse bore to first and second outward openings, respectively; first and second discharge lines communicating with the outward openings of said first and second discharge passages, respectively; a second valve member received in said transverse bore and having a valve passage communicating with said inlet passage, said second valve member being movable between a first discharge position in which said valve passage communicates with first discharge passage, a second discharge position in which said valve passage communicates with said second discharge passage, and an intermediate position in which said valve passage communicates with neither one of the discharge passages; first and second feed lines for said miscible liquids communicating with said first and second disc passages, respectively, and operating means comprising an operating handle mounted on said second valve member and connected to said first valve member for the independent movement of said first and second valve members between the first, second and intermediate positions thereof.

2. Mixing valve as defined in claim 1, wherein the transverse bore comprises a cylindrical central section, first and second cylindrical outer sections coaxial to said central section and having an increased diameter, and first and second transition sections disposed between said central section and said first and second outer sections, respectively, the inlet passage opens into said central section, said first and second discharge passages open into said first and second transition sections, respectively, said second valve member is received within said transverse bore for rotational and axial movement, said second valve member having mounted thereon first and second outward sealing rings sealingly engaging the inner surface of said first and second outer sections, respectively, of said transverse bore, and first and second inner sealing rings adapted to sealingly engage in the intermediate position of said second valve member the inner surface of the central section of said transverse bore, said second valve member further having an annular valve passage defined between said first and second inner sealing rings and communicating with said inlet passage, said second valve member being axially movable between first and second discharge positions, in which the respective one of the first and second inner sealing rings is moved out of contract with the central section of said transverse bore, thus providing a passage between said inlet passage and the respective one of the first and second discharge passages.

3. Mixing valve as defined in claim 1, wherein said transverse bore has a cylindrical inner surface, said second valve member is received in said transverse bore for only rotational movement, and is provided with a valve passage which in all rotational positions of said second valve member communicates with said inlet passage, and in certain different rotational positions of said second valve member communicates with one of said discharge passages.

4. Mixing valve as defined in claim 1, wherein at least one of said first and second discharge passages extends to a circumferential annular groove on said first valve member, each groove defines a separate annular space between said first valve member and said valve housing, at least one of said first and second discharge lines extends through the wall of said valve housing and communicates with the respective annular groove.

5. Mixing valve as defined in claim 1, wherein one of said first and second discharge passages communicates with a respective discharge line extending through said valve disc coaxially to the rotary axis of said first valve member.

6. Mixing valve as defined in claim 1, wherein one of said first and second discharge passages communicates with a respective discharge line directly connected to said first valve member.

7. Mixing valve as defined in claim 1, wherein said first valve member is provided with guide means restricting the movement of said operating handle relative thereto.

8. Mixing valve as defined in claim 1, wherein said first and second disc passages are disposed close to each other in the same radial distance from the rotary axis of said first valve member, and the shape and dimension of the opening of said inlet passage on the valve face of said first valve member are adapted to provide in the intermediate positions such cross-sections of communication with both of said first and second disc passages which together permit an unreduced discharge volume.

9. Mixing valve as defined in claim 1, wherein said first and second disc passages are disposed in different radial distances from the rotary axis of said first valve member.

10. Mixing valve as defined in claim 1 adapted for mixing treated and non-treated portions of the same liquid, especially cold water and hot water, wherein said valve disc is provided with a first disc passage disposed at a radial distance from the rotary axis of said first valve member and communicating with a first feed line for untreated liquid, a second disc passage disposed coaxially with said rotary axis and communicating via connecting line to the outlet of a liquid treating device, and a third disc passage disposed in the same radial distance from said rotary axis as the first disc passage, said third disc passage communicating via a connecting line to the inlet of said liquid treating device, and

said first valve member is further provided with a reversing channel separated from the opening of said inlet passage by a dividing edge which in accordance with the relative position of said dividing edge to said first disc passage provides for a corresponding partial flow through said reversing channel, said third disc passage, said liquid treating device and said second disc passage into said inlet passage.

11. Mixing valve as defined in claim 1, wherein said transverse bore after insertion of said second valve member is tightly closed on both ends thereof by cover members, each of said first and second transition sections forms an annular valve seat, said second valve member is divided into a first and a second valve piston biased by first and second spring means, respectively, against said first and second annular valve seats respectively, and said operating handle is mounted for pivotal motion in opposite directions adapted to remove one of said valve pistons from the corresponding annular valve seat.
